COMPOSITION SHINGLE

Trush McAvoy, Cincinnati, Ohio

Application February 28, 1941, Serial No. 381,092

3 Claims. (Cl. 108—8)

The most widely used composition roofing material other than saturated felt roll roofing consists of what are termed strip shingles. These are relatively stiff and fairly thick strips of the size of say, three interspaced individual shingles, with unslotted backs and with the portions to be exposed slotted so as to give the appearance of interspaced individual shingles. These products are ordinarily made of heavy asphalt saturated felt having an asphalt coating thereon in which is imbedded particles of colored slate or other granular material which obscures the asphalt.

A difficulty attendant upon laying of strip shingles is due to water being dammed up on the roof beneath the strip shingles by the back edge thereof. Water which gets to the back edge of strip shingles will be conducted for quite a distance and held back from flowing away by an amount which the thickness of the shingle material will keep from flowing away. Strip shingles are not ordinarily laid with spacing between the lateral edges but are butted against each other laterally, and in this way water may be conducted along the roof for many feet and held against running away. Often under such circumstances some hole in the sub-structure will form a passage for water which will run through the roof into the building below. It is quite difficult to trace the cause of the leak under such circumstances as the water has perhaps run for quite a distance along the roof, before finding a passageway for escape.

A frequent source of such leaks is at the valleys where the roof surfaces meet at an angle. A valley strip usually of metal is laid in the valley and the strip shingles simply extend over the edge of the valley strip. This leaves exposed the space just above the back end of each strip shingle, and water can thus get into the space and be dammed up, as above described.

In order to avoid this difficulty and make a strip shingle which will be inexpensive, and laid as usual, I have provided for a beveling off of the back edge of each strip shingle to a fairly thin edge. Thus water which can get into the space above any shingle on the roof will drain away and not run along the protected or dammed up line which a regular full thickness back edge will provide against the roof.

By this simple expedient, I do not depart from the economy of making the strip shingles or laying them except for the slight cost of stamping, beveling or otherwise trimming the back edge of each shingle to a sharp edge, the bevel being only on the uppermost or face side of the shingle and

the underside of the shingle without break so that it can be nailed down flat on the roof.

I accomplish my object by that certain construction and arrangement of parts to be herein-
5 after more specifically pointed out and the novelty residing therein will be set forth in the claims that follow to which reference is hereby made.

In the drawing:

Figure 1 is a fragmentary perspective illustrating a valley of a roof, the roof being covered with my improved shingles.

Fig. 2 is a sectional view taken along the line 10 2—2 of Fig. 1.

Fig. 3 is a perspective view showing my improved shingle, and

Fig. 4 is a perspective illustrating a modification of my shingle.

In Fig. 3 I have illustrated a strip shingle 10 having slots 11 to provide a finished appearance of individual shingles. The upper edge of the shingle is beveled as at 12. Referring now to Fig. 2, I have shown a roof structure formed of sheeting 13 and shingles 10. It will here be apparent that rain water or other condensed moisture which may collect beneath the shingles, as in the space 14, will not be retained therein but will be immediately drained away due to the beveled edge 12 of the succeeding lower shingle. Also 20 the water will not be conducted along the upper edge of the shingle to a location remote from the source of entry as does occur with the conventional shingle having a square upper edge which edge, in conjunction with the inclined roof 25 surface, forms a V-shaped trough or channel preventing immediate escape of the water.

The strip shingles, as already noted, have a surface resulting from imbedded particles of colored slate or other granular material to obscure the black color of the asphaltic coating common to composition shingles. This permits seepage away of the water without damming effect by superimposed shingle strips.

In Figure 1 a valley flashing is indicated at 45 15 and the arrows indicate downward flow of water therein. It is to be noted that some of the water flowing down the valley is certain to strike the upper edges of the shingles and be diverted from the desired course of flow. With my improved formation this water will be immediately drained from beneath the shingles.

In Figure 4 the shingle 10a has the usual beveled upper edge 12 and is also provided with channels or depressed portions 16. The channels 50 55 16 serve to facilitate drainage of water and will

be unobserved in the finished structure due to overlapping of successive shingles.

It will be understood that I am not to be limited to the strip shingle type of roofing as shown in the drawing but that my invention is readily applicable to roofing slabs or strips not demarcated to simulate a series of individual shingles and to those having irregular lower edges for decorative purposes. My invention will also have utility in the normal width individual composition shingle. These are interspaced throughout as laid and between each shingle there is thus a normally adequate water escape channel, but the escape of water would be prevented by the edge of the overlapped shingles and so on down the roof. Thus I am not to be limited to the precise formation as shown and described but by what I claim to be new and patentable.

It is not necessary that saturated and coated roofing felt be the composition used according to my invention, although there must be a roughened surface on the underlying faces of the composition units or water cannot escape and seep to the outer surface of the roof.

In the claims that follow I use the term "strip shingle" to indicate not only roofing strips which are cut to simulate a series of interspaced individual shingles, but strips having other types of exposed edges, but having a width factor which makes them readily distinguishable from normal size wooden or composition individual shingles which are laid with lateral interspacing.

Having thus described my invention what I claim as new and desire to secure by Letters Patent, is:

1. A composition strip shingle having the body

portion thereof which is overlapped in laying of substantially uniform thickness and an upper edge for said portion which is sharply slanted from the top surface toward the bottom surface thereof, thus presenting substantially no water retaining edge along the upper line of the shingle as laid and indentations interspaced along said upper edge extending into the sloped off portion, and depending thence toward the exposed part of the shingle, to serve as water drainage channels.

2. A composition strip shingle having its area to be exposed in laying cut to simulate individual spaced shingles, and having its upper portion to be overlapped in laying of substantially uniform thickness except at the upper edge where the same is sharply sloped off from the top face toward the bottom face, the apex of the slope being at the upper edge, for the purpose described and indentations interspaced along said upper edge extending into the sloped off portion, and depending thence toward the exposed part of the shingle, to serve as water drainage channels.

3. A composition shingle having the body portion thereof which is overlapped in laying of substantially uniform thickness and an upper edge for said portion which is sharply slanted from the top surface toward the bottom surface thereof, thus presenting substantially no water retaining edge along the upper line of the shingle as laid and indentations interspaced along said upper edge extending into the sloped off portion, and depending thence toward the exposed part of the shingle, to serve as water drainage channels.

TRUSH McAVOY.
